(57) **CLAIM**

The ornamental design for cooking appliances and utensils, as shown.

DESCRIPTION

FIG. 1 is a front perspective view of a first embodiment of a cooking appliance showing our new design;

FIG. 2 is a front elevation view of the cooking appliance of FIG. 1;

FIG. 3 is rear elevation view of the cooking appliance of FIG. 1;

FIG. 4 is a left side elevation view of the cooking appliance of FIG. 1;

FIG. 5 is a right side elevation view of the cooking appliance of FIG. 1;

FIG. 6 is a top plan view of the cooking appliance of FIG. 1;

FIG. 7 is a bottom view of the cooking appliance of FIG. 1;

FIG. 8 is a front perspective view of a second embodiment of a cooking appliance showing our new design;

FIG. 9 is a front elevation view of the cooking appliance of FIG. 8;

FIG. 10 is rear elevation view of the cooking appliance of FIG. 8;

FIG. 11 is a left side elevation view of the cooking appliance of FIG. 8;

FIG. 12 is a right side elevation view of the cooking appliance of FIG. 8;

FIG. 13 is a top plan view of the cooking appliance of FIG. 8;

FIG. 14 is a bottom view of the cooking appliance of FIG. 8;

FIG. 15 is a front perspective view of an enlarged cooking appliance handle showing our new design;

FIG. 16 is a front elevation view of the enlarged cooking appliance handle of FIG. 15;

FIG. 17 is rear elevation view of the enlarged cooking appliance handle of FIG. 15;

FIG. 18 is a left side elevation view of the enlarged cooking appliance handle of FIG. 15;

FIG. 19 is a right side elevation view of the enlarged cooking appliance handle of FIG. 15;

FIG. 20 is a top plan view of the enlarged cooking appliance handle of FIG. 15;

FIG. 21 is a bottom view of the enlarged cooking appliance handle of FIG. 15;

(Continued)

FIG. 22 is a front perspective view of an enlarged cooking appliance utensil showing our new design;
 FIG. 23 is a front elevation view of the enlarged cooking appliance utensil of FIG. 22;
 FIG. 24 is rear elevation view of the enlarged cooking appliance utensil of FIG. 22;
 FIG. 25 is a left side elevation view of the enlarged cooking appliance utensil of FIG. 22;
 FIG. 26 is a right side elevation view of the enlarged cooking appliance utensil of FIG. 22;
 FIG. 27 is a top plan view of the enlarged cooking appliance utensil of FIG. 22;
 FIG. 28 is a bottom view of the enlarged cooking appliance utensil of FIG. 22;
 FIG. 29 is a front perspective view of an enlarged cooking appliance component showing our new design;
 FIG. 30 is a front elevation view of the enlarged cooking appliance component of FIG. 29;
 FIG. 31 is rear elevation view of the enlarged cooking appliance component of FIG. 29;
 FIG. 32 is a left side elevation view of the enlarged cooking appliance component of FIG. 29;
 FIG. 33 is a right side elevation view of the enlarged cooking appliance component of FIG. 29;
 FIG. 34 is a top plan view of the enlarged cooking appliance component of FIG. 29; and,
 FIG. 35 is a bottom view of the enlarged cooking appliance component of FIG. 29.
